UNITED STATES PATENT OFFICE.

BURRITT A. PARKS, OF GRAND RAPIDS, MICHIGAN.

VALVE STRUCTURE.

Application filed December 16, 1922. Serial No. 607,314.

To all whom it may concern:

Be it known that I, BURRITT A. PARKS, a citizen of the United States, residing at Grand Rapids, in the county of Kent and State of Michigan, have invented new and useful Improvements in Valve Structures, of which the following is a specification.

The present invention relates to valve structures, particularly such as are employed 10 in steam lines containing heating radiators; and its object is to provide improved means whereby the water of condensation accumulating in such lines may be automatically discharged.

15 This and any other objects hereinafter appearing are attained by, and the invention finds preferable embodiment in, the structure hereinafter particularly described in the body of this specification and illustrated by 20 the accompanying drawings, in which:—

Figure 1 is a longitudinal sectional view of a valve structure taken on a vertical plane corresponding to line 1—1 of Figure 2;

25 Figure 2 is a transverse sectional view of the same taken on planes corresponding to line 2—2 of Figure 1; and

30 Figure 3 is a side view of a steam line containing a heating radiator and equipped with my valve structure.

In steam lines containing heating radiators and the like, there is usually provided an extension of the vertical steam-supply pipe or "riser" having means for discharging 35 the water of condensation accumulating therein into a return pipe into which return pipe the steam passes from the radiator usually through similar water-discharging means.

40 My object is to provide a unitary structure wherein automatic water-discharging means are combined with the valve which controls the passage of the steam through the radiator, thus dispensing with certain 45 parts hitherto employed in such steam lines and with the necessary connecting of such parts with other portions of the line.

In the embodiment of the invention chosen for illustration by the drawings and for detailed description in the body of this specification, the steam line designated generally 1, contains a heat radiator 2, only two "sections" of which are shown. A unitary structure or member 3 receives the steam 55 into its chamber 4 through its inlet port 5 from the steam supply pipe or "riser" 6

and discharges the steam through said chamber's outlet port 7 into the heat radiator 2. In the chamber 4 is a hollow valve 9 whose lower end carrying the ring packing 10 seats in the valve seat 12 and controls, as desired, the passage of steam through the member 3 and into the radiator, being operated for this purpose by the handle 13 whose vertical shaft is threaded 60 at 14 in the upper end of said valve. A restricted by-pass in this valve structure is provided, the same as shown at 15 being desirably through the bottom of the valve 9 itself. A conical valve 16 inside the hollow 65 valve 9 controls this by-pass, being carried by a suitable heat-expansible and cold-contractible element 17 also located in the hollow valve 9, and operating by decreasing 70 heat and consequent contraction to raise the valve 16 and open the by-pass, and by increasing heat and consequent expansion to lower said valve and close the by-pass.

It will be seen that if the valve 9 is closed 75 to shut off the steam, and if water condenses in the chamber 4 by thus lowering the heat, this lowering of the heat will contract the element 17 and open the by-pass valve 16 so that such water will flow through the 80 by-pass into the radiator and thence out 85 through the return pipe 18; and that when the steam is turned on, or the element 17 otherwise becomes heated, the by-pass will be closed.

The invention being intended to be pointed out in the claims, is not to be limited to or by details of construction of the particular embodiment thereof illustrated by the drawings or hereinbefore shown or 90 described.

I claim:—

1. In a steam line: a member having a chamber with steam inlet and outlet ports; a steam-controlling valve in the chamber between said ports and having a by-pass therethrough; means manually operated for moving said valve to closed position and manually operated for moving the same to open position; a valve for controlling the by-pass; means carried by the first-mentioned 100 valve on the pressure side of the by-pass valve and operated by decreasing heat for opening and by increasing heat for closing the by-pass valve.

2. In a steam line containing a heat radiator: a member having a chamber with a steam inlet port and a steam outlet port to 110

the radiator; a hollow valve in the chamber for controlling the passage of steam to the radiator, and having a by-pass therethrough; means manually operated for moving said

5 valve to closed position and manually operated for moving the same to open position; a valve in the first-mentioned valve for controlling the by-pass; means in the first-

mentioned valve on the pressure side of the by-pass valve and operated by decreasing 10 heat for opening and by increasing heat for closing the by-pass valve.

In testimony whereof I have hereunto set my hand at Grand Rapids, Michigan, this 11th day of December, 1922.

BURRITT A. PARKS.
